UNITED STATES PATENT OFFICE.

WILLIAM D. DOTY, OF STREATOR, ILLINOIS, ASSIGNOR OF ONE-HALF TO MATTHEW W. JACK, OF STREATOR, ILLINOIS.

AIR-PURIFYING AND VENTILATING DEVICE.

1,219,811.

Specification of Letters Patent. Patented Mar. 20, 1917.

Application filed January 8, 1916. Serial No. 71,040.

To all whom it may concern:

Be it known that I, WILLIAM D. Doty, a citizen of the United States, residing at Streator, in the county of La Salle and State of Illinois, have invented certain new and useful Improvements in Air-Purifying and Ventilating Devices, of which the following is a specification.

This invention relates to air purifying and ventilating devices, and has for one of its objects to provide a simply constructed device which may be arranged in a window opening or like locality and which operates to screen and purify the air and also to provide suitable ventilation without creating drafts.

Another object of the invention is to provide a simply constructed device which may be readily adjusted to windows or other openings of varying widths without detaching any of the parts.

Another object of the invention is to provide a device of this character including coacting frames slidably engaged and which are constructed entirely of metal and adapted to support the screening or purifying fabric.

With these and other objects in view, the invention consists in certain novel features of construction as hereinafter shown and described and then specifically pointed out in the claims; and in the drawings illustrative of the preferred embodiment of the invention—

Figure 1 is an elevation of the improved device;

Fig. 2 is a plan view, and

Fig. 3 is an end elevation of the same;

Fig. 4 is a perspective view of a portion of one of the side members of one of the frames;

Fig. 5 is a perspective view of a portion of one of the end members of one of the frames;

Fig. 6 is a perspective view from beneath of a portion of one of the side members of the coacting frame;

Fig. 7 is a perspective view from beneath of a portion of one of the end members of the last-mentioned frame;

Fig. 8 is an enlarged transverse section on the line 8—8 of Fig. 1;

Fig. 9 is an enlarged longitudinal section on the line 9—9 of Fig. 1;

Fig. 10 is a view similar to Fig. 1 illustrating a modification in the construction;

Fig. 11 is a longitudinal section on the line 11—11 of Fig. 10;

Fig. 12 is a vertical section on the line 12—12 of Fig. 10;

Fig. 13 is a perspective view of a portion of one of the modified frames shown in Fig. 10;

Fig. 14 is a perspective view of a portion of the other modified frame shown in Fig. 10.

Corresponding and like parts are referred to in the following description and indicated in all the views of the drawings by the same reference characters.

The improved device includes coacting frames slidably engaged and each having lateral projections provided with fabric engaging elements, such as pins or spurs, with the adjacent end members of each frame provided with a lateral off-set or projection extending toward the fabric material of the other frame to cut off the circulation of air between the portions of the fabric members which overlap. The frame members may be of any suitable material, either metal or wood, and for the purpose of illustration the frames are shown constructed of metal in Figs. 1 to 9, and shown constructed of wood in Figs. 10 to 14. When constructed of metal one of the frames comprises side members 10—11 spaced apart and end members 12—13 likewise spaced apart. The side member 10 is turned at its outer edge to form a longitudinally directed guide-way 14, while the side member 11 is formed with a similar guide-way 15. The end member 12 is preferably turned over at its outer edge, as shown at 16, to strengthen and reinforce it, while the end member 13 is turned laterally at one edge, as illustrated at 17, to form a cut-off rib, the object to be hereinafter explained. At their terminals the end members 12—13 overlap the terminals of the side members 10—11 and are soldered or otherwise secured thereto. The side member 10 is provided with a lateral projection 18 while the side member 11 is provided with a similar lateral projection 19,

The end member 12 is provided with a similar lateral projection 20, while the end member 13 is provided with a similar lateral projection 21. The projections 18—19—20—21 are formed at the inner edges of the frame members, as shown. The inner lateral projections are provided with fabric engaging elements in the form of studs or pins, indicated at 22. When constructed of metal, as shown in Figs. 1 to 9, the fabric engaging elements are integral with the lateral projections, as shown more clearly in Figs. 4 and 5.

The coacting frame when constructed of metal comprises side members 23—24 and end members 25—26. The side members 23—24 slidably engage the guide-ways 14—15, while the end member 25 is turned over at the outer edge, as indicated at 27, to reinforce and strengthen the latter. The side members 23—24 overlap the terminals of the end members 25—26 and are secured thereto by soldering or by other suitable means. The side member 23 is provided with a laterally directed projection 28, while a similar lateral projection 29 extends from the side member 24. A similar lateral projection 30 extends from the end member 25, while a lateral projection 31 extends from the end member 26. The lateral projections 28—29—30—31 project from the coacting frame member at the side opposite to the projections 18—19—20—21 of the other frame, and are provided with fabric securing studs or pins 32.

The fabric which is secured to the studs is indicated conventionally at 33 and may be of any suitable material, either cloth or screen material. If cloth is engaged as a fabric the latter will preferably be of coarse mesh to permit the air to freely pass while excluding dust or other impurities and may be impregnated with disinfecting material or the like. As before stated, the end member 13 is turned down at one edge, as indicated at 17, to closely engage the adjacent face of the fabric which is attached to the coacting frame members. By this means the edge 17 forms a cut-off to prevent the air passing between the portions of the fabric which overlap. By this arrangement it will be obvious that by employing the studs or pins to support the fabric the latter may be readily attached to, detached from, renewed or changed as required without destroying or disconnecting any of the parts. By arranging the frames to slidably engage it will be obvious that the device may be increased or decreased in length to adapt it to windows or other openings of various widths.

The improved device is designed to be employed more particularly beneath the lower sash, or above the upper sash of a window, or both above and below, if preferred. The end members of the frames engage in the

guide-ways of the sash, and the sashes close against the frame members when the latter are adjusted. The frames may be of any required size and it is not desired to limit the invention in this respect.

When the frames are constructed from wood the arrangement shown in Figs. 10 to 14 will be employed. One of the frames when constructed from wood will include side members 34—35 and end members 36—37, while the coacting frame is formed with side members 38—39 and end members 40—41. The members 34—35—36—37 are each formed with rabbets, indicated at 42, the portion of the frames externally of the rabbets corresponding to the lateral projections of the structure shown in Figs. 1 to 9. The members 38—39—40—41 of the coacting frame are likewise provided with a similar rabbet, indicated at 43, with the portions of the frame members externally of the rabbet corresponding to the lateral projections of the coacting frame shown in Figs. 1 to 9. The end member 37 of one of the frames is formed wider than the frame member 36, while the frame member 41 is likewise wider than the frame member 40, as illustrated in Fig. 11. The confronting faces of the side members 34—35 and 38—39 are formed with longitudinal grooves, indicated respectively 44—45, while the wider portions of the members 37—41 are provided with ribs 46—47 to engage respectively in the channels. By this means the frame members are slidably engaged and held from displacement by the coaction of the guide channels 44—45 and the ribs 40—47. In the modification shown in Figs. 10 to 14 a plurality of pins, indicated at 48, project from the frame members within the rabbets to support the fabric material, now shown, and thus operating in the same manner and for the same purpose as the studs 22 in the structure shown in Figs. 1 to 9.

Having thus described the invention, what is claimed as new is:—

1. A device of the class described, comprising coacting frames with their confronting faces slidably engaging, the body portion of each frame member having a part directed laterally therefrom and the outer edge of each laterally directed part provided with a plurality of spurs spaced apart and adapted to be engaged by a fabric member.

2. A device of the class described, comprising coacting frames, one of said frames having longitudinally directed guides to slidably receive the other frame and each of said frames having a part directed laterally therefrom and the outer edge of each laterally directed part provided with a plurality of spurs spaced apart and adapted to be engaged by a fabric member.

3. In a device of the class described, a

frame having lateral projections at the inner edges of its members with fabric engaging elements carried by the projections, the side members of said frame having longitudinally directed guideways and one of the end members having a lateral projection at its outer edge, and a coacting frame having lateral projections at the inner edges of its members carrying fabric engaging elements, 5 and with one of its end members formed with another lateral projection, the side members of said last-mentioned frame slidably engaging the guides of the first-mentioned frame.

15 4. In a device of the class described a frame formed of side members having guide devices at their outer edges and lateral projections at their inner edges, said lateral projections each carrying a plurality of spurs 20 extending in parallel relation to the side members, and end members secured by their terminals to the side members and each having a lateral projection at its inner edge, said last mentioned projections each carrying 25 a plurality of spurs directed in parallel relation to the end members, said spurs adapted to be engaged by a fabric element.

5. In a device of the class described, a frame formed of side members having lateral projections at their inner edges, each of 30 said projections carrying a plurality of spurs directed in parallel relation to the frame members, and end members secured

by their terminals to the side members and each having a lateral projection at its inner 35 edge, each of said last mentioned projections carrying a plurality of spurs directed in parallel relation to the frame members, said spurs adapted to be engaged by a fabric element.

6. In a device of the class described, a frame formed of side members having guide devices at their outer edges and lateral projections at their inner edges and carrying fabric supporting elements, and end members secured by their terminals to the side members and each having a lateral projection at its inner edge and carrying fabric supporting elements, one of said end members having a lateral projection at the edge 45 opposite to the fabric supporting elements thereof, and a coacting frame formed of side members with lateral projections carrying fabric supporting elements and slidably 50 engaging the guide devices of the first-mentioned frame, and end members secured at their terminals to the side members and with lateral projections carrying fabric supporting elements, the outer edge of one of the end members of said last-mentioned frame having a lateral projection at the edge 55 opposite to the fabric supporting elements thereof.

In testimony whereof I affix my signature.

WILLIAM D. DOTY. [L. S.]
